UNITED STATES PATENT OFFICE.

HOWARD M. BARBER, OF STONINGTON, CONNECTICUT, ASSIGNOR, BY MESNE ASSIGNMENTS, TO C. B. COTTRELL & SONS COMPANY, OF NEW YORK, N. Y., A CORPORATION OF DELAWARE.

ROTARY SHEET-PRINTING MACHINE.

1,152,069.

Specification of Letters Patent. Patented Aug. 31, 1915.

Application filed December 18, 1912. Serial No. 737,432.

To all whom it may concern:

Be it known that I, HOWARD M. BARBER, a citizen of the United States, and resident of Stonington, in the county of New London and State of Connecticut, have invented 5 a new and useful Improvement in Rotary Sheet-Printing Machines, of which the following is a specification.

This invention relates to rotary sheet 10 printing machines and particularly to that class of machines which may be used for single or multi-color printing and consists in a novel sheet feeding mechanism arranged to feed printing sheets from one 15 source of sheet supply and either printing sheets or slip sheets from another source of sheet supply into the machine, as may be desired.

In single color and in most multi-color 20 work on machines of the class above described, it is seldom, if ever, necessary to use slip sheets between the printed sheets to prevent offsetting or smutting. Printing sheets may then be fed into the machine 25 from two different sources and thereby double the printed product delivered from the machine as the possible operating speed of a rotary printing machine of this character far exceeds the speed of a single feeder. 30 In some instances, it becomes very desirable to deliver a slip sheeted product and slip sheets may then be fed from one of the sources instead of the printing sheets.

In the accompanying drawings, Figure 35 1 represents in side elevation so much of a rotary printing machine as will give a clear understanding of my invention, the parts being in the position which they assume when printing sheets are being fed from one 40 source to the impression cylinder and slip sheets fed from another source to the delivery cylinder of a printed sheet delivery mechanism, Fig. 2 is a detail section showing the cam mechanism for controlling the 45 operation of the grippers on the transfer cylinder when used for slip sheeting, Fig. 3 is a vertical longitudinal central section with the parts in the position shown in Fig. 1 for delivering a slip sheeted product, Fig. 50 4 is a vertical longitudinal section taken adjacent to the farther side frame with the parts in the position shown in Fig. 1, Fig. 5 is a view similar to Fig. 1, with the parts in the position which they assume for de-

livering a double non-slip sheeted product, 55 Fig. 6 is a detail section showing the cam mechanism for controlling the action of the grippers on the transfer cylinder when used for feeding printing sheets into the machine, and Fig. 7 is a vertical longitudinal central section through the machine with the parts in the position shown in Fig. 5 arranged for delivering a double non-slip sheeted product.

The machine is herein shown as having 65 two plate cylinders 1, 2, and a single impression cylinder 3 having two impression surfaces 4, 5, and two sets of sheet grippers 6, 7. Two sources of sheet supply are herein shown as tables 8 and 9, the table 8 being arranged to feed printing sheets to the grippers 7 on the impression cylinder and the table 9 being arranged to feed either printing sheets to the grippers 6 of the impression cylinder or slip sheets to the delivery mechanism, as the case may be. 70

A suitable printed sheet delivery may be provided, that shown herein comprising an endless delivery carrier 10, a printed sheet delivery cylinder 11, a delivery reel 12, and 80 suitable guides and rollers 13, 14 interposed between the endless delivery carrier 10 and the reel 12.

The set of grippers on the delivery cylinder 11 is denoted by 15 and the set of grippers on the delivery reel 12 by 16. The sheet feeding mechanism for feeding sheets from the table 9 includes a transfer cylinder 17 and its set of grippers 18.

The table 9 may be raised and lowered for 90 feeding sheets to the upper or the under side of the transfer cylinder 17, the means shown herein comprising two racks 19, 20, depending from the table 9 and a train of gearing 21, 22, 23, 24, connecting the racks 95 with a hand wheel 25. The table 9 is provided with a folding section adjacent to the transfer cylinder 17 for permitting the table to be raised and lowered.

The impression cylinder gear 26 meshes 100 at all times with the delivery cylinder gear 27, which, in turn, meshes at all times with the delivery reel gear 28. This gear 28 meshes with the gear 29 of the feed rollers 14.

The transfer cylinder 17 is moved into and out of operative engagement with the impression cylinder 3 and the delivery cyl-

inder 11 by bringing the transfer cylinder gear 30 into or out of mesh with the impression cylinder gear 26 or into or out of mesh with the delivery cylinder gear 27.

5 When the transfer cylinder gear 30 is in mesh with the plate cylinder gear 27 and out of mesh with the impression cylinder gear 26 and the table 9 is raised, the transfer cylinder 17 is arranged to feed slip

10 sheets directly to the delivery cylinder 11.

When the transfer cylinder gear 30 is brought into mesh with the impression cylinder gear 26 and out of mesh with the delivery cylinder gear 27 and the table 9 is lowered, the transfer cylinder 17 is arranged to feed printing sheets directly to the impression cylinder 3. The means which I have shown for raising and lowering the transfer cylinder 17 comprises a rock shaft

20 31, its handle 32 and crank arms 33 connected to the auxiliary frame 34, which carries the transfer cylinder 17, through the connecting rods 35. A stop 36 is provided for limiting the rotary movement of the

25 crank shaft 31 when the auxiliary frame 34 has been raised to bring the transfer cylinder 17 into operative engagement with the impression cylinder 3. Removable blocks

30 37, one only of which is herein shown, are inserted between the auxiliary frame 34 and the main frame of the machine when the auxiliary frame is raised. When it is desired to lower the frame to bring the transfer cylinder 17 into operative engagement

35 with the delivery cylinder 11, the blocks 37 are removed. The set of grippers 18 on the transfer cylinder 17 are reversible.

When the table 9 is in its raised position, a sheet stop 38 is provided, which sheet stop 40 is operated from a cam shaft 39 through the rock shaft 40, its arm 41, the rock lever 42, the connecting rods 43, 44, the rock lever 45 and the cam 46. When the table 9 is in its lowered position, the sheet stop 38 is removed and a sheet stop 47 is provided which is connected to the rock lever 42 through the rock lever 48 and connecting rod 49. When this sheet stop 47 is used, the connecting rod 43 is removed.

50 A stationary adjustable cam 50 is provided, which cam is mounted in the position shown in full lines in Fig. 4 for opening the grippers 18 to transfer slip sheets to the grippers 15 of the delivery cylinder 11 and this cam 50 is shown in dotted lines on Fig. 4 in position to open the grippers 18 to transfer printing sheets therefrom to the grippers 6 on the impression cylinder 3.

A stationary cam 51 is provided for opening the grippers 15 on the delivery cylinder 11 to receive slip sheets from the transfer cylinder 17 when a slip sheeted product is being delivered.

55 A stationary cam 52 is provided for opening the grippers 15 on the delivery cylinder

11 for receiving printed sheets from either both sets of impression cylinder grippers 6 and 7 or from the grippers 7 according to whether a single or double product is being delivered.

70 A stationary cam 53 is provided for opening the delivery cylinder grippers 15 to transfer the sheets therefrom to the reel grippers 16.

A stationary cam 54 is arranged in position to open the grippers 16 on the reel 12 for receiving the sheets from the delivery cylinder 11.

75 A stationary cam 55 is provided for opening the grippers 6 and 7 to deliver either 80 sheets from both grippers or from one set of grippers to the delivery cylinder grippers 15.

A stationary cam 56 is provided for opening the grippers 6 to receive a printing sheet 85 from the grippers 18 on the transfer cylinder when a double non-slip-sheeted product is being delivered.

A stationary cam 57 is provided for opening the reel grippers 16 to deliver the sheets 90 onto the guides 13 to be forwarded by the feed rollers 14 to the endless delivery carrier 10.

A sheet stop for the table 8 is denoted by 58, which stop is mounted to swing on a 95 shaft 59 and is normally held in its lowered position by the spring pressed means 60. The sheet stop is raised to permit the feeding of a sheet to the grippers 7 and held raised throughout the impression surface 5 100 by means of a cam 61 mounted to rotate with the impression cylinder 3, which cam engages the rock arm 62 of the said sheet stop.

The sheet stop 58 is also raised and held in its raised position to permit the passage 105 of the next succeeding sheets on the impression surface 4 when a double product is being delivered, by means of a fixed cam 63 mounted to rotate with the cylinder 3.

The grippers 7 on the impression cylinder 3 are opened and closed to receive and grasp a printing sheet from the table 8 by a tumbler cam mechanism, the tumbler cam being denoted by 64, the tumbler pins by 65, 66, the rock arm by 67 and the cam for controlling the rock arm by 68, which cam is fixed on the shaft 69 of the impression cylinder. The tumbler cam mechanism is shown herein as being arranged to operate only the set of grippers 7. When the grippers 18 on the transfer cylinder 17 are arranged for receiving slip sheets from the table 9 they are opened and closed by a tumbler cam mechanism, the tumbler cam on the gripper shaft being denoted by 70, the 115 tumbler pins by 71, 72, the rock shaft by 73, and the cam for controlling the movements of the rock shaft by 74. This cam is mounted upon a cam shaft 39 driven from the shaft 76 of the transfer cylinder 17 through 120

125

130

the gears 77, 78. When the grippers 18 are reversed and arranged to receive printing sheets at the under side of the transfer cylinder 17, a second tumbler cam mechanism 5 is provided which includes the tumbler pins 79, 80, arranged to engage the tumbler cam 70, and the rock shaft 81 which is controlled by the cam 74 above referred to. When the tumbler cam mechanism for operating the 10 grippers to receive slip sheets is used, the other tumbler cam mechanism is removed. When the tumbler cam mechanism for operating the grippers to receive printing sheets is in use, the rock lever 73 of the other 15 cam mechanism is disconnected from the cam 74 as shown in Fig. 6, and the tumbler pins 71 and 72 are held out of their operative position by set screws 82 shown in Fig. 5.

20 The support 83 for the rock shaft 81 is preferably carried by one of the spacing blocks 37 so that the cam mechanism may be readily removed with the said block 37.

With the parts in the position to print 25 and deliver a single slip-sheeted product, the operation is as follows: A printing sheet is fed from the table 8 to the grippers 7 on the impression cylinder and carried thereby past the plate cylinders and is delivered to the 30 delivery cylinder 11 during one revolution of the said delivery cylinder. The slip sheets are fed from the table 9 to the grippers 18 on the transfer cylinder 17 and are delivered therefrom to the grippers 15 of 35 the delivery cylinder 11 the next revolution of said delivery cylinder. The delivery cylinder 11 successively transfers the printed sheets and slip sheets to the grippers 16 of the delivery reel 12 and are transferred 40 thereby to the guides 13 where they are fed by the rollers 14 to the endless delivery carrier 10. When a double non-slip-sheeted product is to be delivered, the grippers 18 on the transfer cylinder 17 are reversed as 45 shown in Fig. 7, the cylinder 17 is raised by the hand wheel 32 out of operative engagement with the delivery cylinder 11 and into operative engagement with the impression cylinder 3. The spacing blocks 37 are then 50 inserted and the tumbler cam mechanism for operating the grippers in this position is brought into operative position. The other cam mechanism is thrown out of its operative position. The printing sheets are fed 55 as before from the table 8 to the grippers 7 and after the printing operation are transferred thereby to the grippers 15 on the delivery cylinder 11 one revolution thereof. Another printing sheet is fed from the table 60 9 to the grippers 18 on the transfer cylinder 17 and is transferred thereby to the grippers 6. After the printing operation, the sheet is then transferred to the grippers 15 of the delivery cylinder 11 the next succeeding revolution of the said cylinder 11. The

cylinder 11 delivers to the delivery reel 12 a printed sheet every revolution of the delivery cylinder and the printed sheets are transferred successively from the delivery reel through the guides 13 to the endless delivery carrier 10. In the arrangement of the parts as herein shown, the transfer cylinder and the delivery cylinder are each arranged to travel two revolutions for one revolution of the impression cylinder. 70

While the parts are herein shown as being arranged when a slip sheeted product is being delivered to have the grippers 15 on the cylinder 11 take a printed sheet and deliver it one revolution and take a slip sheet 80 and deliver it the next revolution they may easily be adjusted so that every second revolution of the cylinder 11 the grippers 15 may first take a printed sheet from the grippers 6 of the impression cylinder and then a slip sheet from the grippers 18 of the feeding cylinder and then transfer the associated printed and slip sheets together to the grippers 16 of the delivery reel 12. To accomplish this last-named result, it would only 85 be necessary to set the feeding device a full revolution back or in advance of the position where alternate printed and slip sheets are delivered every revolution of the cylinder 11. Where a double non-slip-sheeted product is being delivered, it will be seen that the delivery cylinder 11 will deliver a printed sheet every revolution thereof to the delivery reel. 95

By the use of the term "cylinders" in the 100 feeding and delivery mechanisms, I wish to be understood as including any means capable of passing the sheets through the required paths for carrying out the results above described. 105

It is evident that slight changes might be resorted to in the form, construction and arrangement of the several parts without departing from the spirit and scope of my invention; hence I do not wish to limit myself strictly to the structure herein set forth, but

What I claim is:—

1. In a rotary printing machine, an impression cylinder, a delivery mechanism, and a transfer cylinder arranged to feed from a source of sheet supply either printing sheets directly to the impression cylinder or slip sheets directly to the delivery mechanism. 115

2. In a rotary printing machine, an impression cylinder, a delivery cylinder and a transfer cylinder arranged to feed from a source of sheet supply either printing sheets directly to the impression cylinder or slip sheets directly to the delivery cylinder. 120

3. In a rotary printing machine, an impression cylinder, means arranged to feed printing sheets thereto from one source of sheet supply, a delivery mechanism and means arranged to feed from another source of sheet supply either printing sheets di- 125

- rectly to the impression cylinder or slip sheets directly to the delivery mechanism.

4. In a rotary printing machine, an impression cylinder, means arranged to feed printing sheets thereto from one source of sheet supply, a delivery cylinder and means arranged to feed from another source of sheet supply either printing sheets directly to the impression cylinder or slip sheets directly to the delivery cylinder.

5. In a rotary printing machine, an impression cylinder, means arranged to feed printing sheets thereto from one source of sheet supply, a delivery mechanism and a transfer cylinder arranged to feed from another source of sheet supply either printing sheets directly to the impression cylinder or slip sheets directly to the delivery mechanism.

6. In a rotary printing machine, an impression cylinder, means arranged to feed printing sheets thereto from one source of sheet supply, a delivery cylinder and a transfer cylinder arranged to feed from another source of sheet supply either printing sheets directly to the impression cylinder or slip sheets directly to the delivery cylinder.

7. In a rotary printing machine, an impression cylinder having two impression surfaces and their sets of grippers, means arranged to feed printing sheets to one set of grippers from one source of sheet supply, a delivery mechanism and means arranged to feed from another source of sheet supply either printing sheets directly to the other set of impression cylinder grippers or slip sheets directly to the delivery mechanism.

8. In a rotary printing machine, an impression cylinder having two impression surfaces and their sets of grippers, means arranged to feed printing sheets to one set of grippers from one source of sheet supply, a delivery cylinder and means arranged to feed from another source of sheet supply either printing sheets directly to the other set of impression cylinder grippers or slip sheets directly to the delivery cylinder.

9. In a rotary printing machine, an impression cylinder having two impression surfaces and their sets of grippers, means arranged to feed printing sheets to one set of grippers from one source of sheet supply, a delivery mechanism and a transfer cylinder arranged to feed from another source of sheet supply either printing sheets directly to the other set of impression cylinder grippers or slip sheets directly to the delivery mechanism.

10. In a rotary printing machine, an impression cylinder having two impression surfaces and their sets of grippers, means arranged to feed printing sheets to one set of grippers from one source of sheet supply, a delivery cylinder and a transfer cylinder arranged to feed from another source of sheet supply either printing sheets directly to the impression cylinder or slip sheets directly to the delivery cylinder.

11. In a rotary printing machine, an impression cylinder, a delivery cylinder and a sheet transfer cylinder arranged to be brought into and out of operative engagement with either the impression or the delivery cylinder to feed the sheets either directly to the impression cylinder or directly to the delivery cylinder.

12. In a rotary printing machine, an impression cylinder, a delivery cylinder, a transfer cylinder and means for moving it out of operative engagement with the delivery cylinder and into operative engagement with the impression cylinder for feeding printing sheets thereto, and out of operative engagement with the impression cylinder and into operative engagement with the delivery cylinder for feeding slip sheets thereto.

13. In a rotary printing machine, an impression cylinder, a delivery cylinder, a transfer cylinder, means for moving it out of operative engagement with the delivery cylinder and into operative engagement with the impression cylinder for feeding printing sheets thereto and out of operative engagement with the impression cylinder and into operative engagement with the delivery cylinder for feeding slip sheets thereto and means for supplying either printing sheets or slip sheets to said transfer cylinder from a source of sheet supply.

14. In a rotary printing machine, an impression cylinder, a delivery cylinder, a transfer cylinder, means for moving it out of operative engagement with the delivery cylinder and into operative engagement with the impression cylinder for feeding printing sheets thereto and out of operative engagement with the impression cylinder and into operative engagement with the delivery cylinder for feeding slip sheets thereto, a sheet feeding table and means for moving it into position to feed printing sheets to the under side of the transfer cylinder or slip sheets to the upper side of the transfer cylinder.

15. In a rotary printing machine, an impression cylinder, means for feeding printing sheets thereto from one source of sheet supply, a delivery cylinder, a transfer cylinder, means for moving it out of operative engagement with the delivery cylinder and into operative engagement with the impression cylinder for feeding printing sheets thereto, and out of operative engagement with the impression cylinder and into operative engagement with the delivery cylinder for feeding slip sheets thereto and means for supplying from another source of sheet supply either printing sheets or slip sheets to said transfer cylinder.

16. In a rotary printing machine, an impression cylinder, means for feeding printing sheets thereto from one source, a transfer cylinder arranged to feed either printing sheets directly to the impression cylinder or slip sheets directly to the delivery cylinder, said delivery cylinder being arranged to take a printed sheet every revolution thereof from the impression cylinder 10 or a printed sheet one revolution from the

impression cylinder and a slip sheet the next revolution from the transfer cylinder.

In testimony that I claim the foregoing as my invention, I have signed my name in presence of two witnesses, this thirteenth 15 day of December A. D. 1912.

HOWARD M. BARBER.
